UNITED STATES PATENT OFFICE

OTTO KARL LEOPOLD DRUBBA, OF HAMBURG, GERMANY

AIR MOISTENER AND CLEANER

Application filed March 2, 1928, Serial No. 258,600, and in Germany March 25, 1927.

This invention relates to an air-moistener and cleaner, comprising a porous-body dipping into a liquid and arranged above a heating body. According to the invention several liquid-containers are arranged which are connected with the porous body either fixedly or removably and preferably also adjustably.

The apparatus which is designed to be inserted into an air-current, for instance on an element of an air-heater or on a plate arranged above the same or to be placed on a seat of a window and over a heating body in front of said seat or to be placed, on the one hand, on a heating body or plate above said heating body and, on the other hand, suspended on the wall, is illustrated in several forms of construction, by way of example, in the accompanying drawings, in which—

20 Figs. 1 to 3 illustrate the preferred form of construction which is shown in Fig. 1 in side-elevation in

Fig. 2 in front-elevation, and in Fig. 3 in top-plan-view.

25 Figs. 4 to 6 show

Fig. 4 in side-elevation, Fig. 5 in front-elevation and

Fig. 6 in top-plan-view a second form of construction of the apparatus.

30 Figs. 7 to 9 show a third form of construction of the apparatus.

Fig. 7 in side elevation,

Fig. 8 in longitudinal section on line A—B of Fig. 7 and

35 Fig. 9 in top-plan view.

Figs. 10 to 12 show a fourth form of construction of the apparatus,

Fig. 10 in side elevation,

Fig. 11 in front elevation and

40 Fig. 12 in top-plan-view.

Fig. 13 is a view in side elevation of a fifth form of construction of the apparatus.

Fig. 14 shows in side-elevation and

45 Fig. 15 in top-plan-view a sixth form of construction of the apparatus.

Fig. 16 shows in side-elevation, partly in section a 7th form of construction of the apparatus.

50 Fig. 17 is a top-plan-view of Fig. 16, partly broken away.

Figs. 18, 19, 20 and 21 show each another position of the apparatus shown in Figs. 14 and 15.

Fig. 22 is a broken plan view of the porous body showing the provision of perforations 55 therein.

Fig. 23 is a similar view showing a modified form of openings formed in the porous body.

Fig. 24 is an enlarged broken sectional view 60 of the liquid container showing the means for securing the rods connecting the liquid containers.

Figs. 25, 26 and 27 show another form of construction of the device for connecting the 65 two liquid-containers.

Fig. 25 being a side-elevation,

Fig. 26 a front-elevation and

Fig. 27 a top-plan-view.

Fig. 28 shows in top-plan-view a device 70 for adjusting the liquid-containers and for securing the same in the adjusted position.

In the apparatus shown in Figs. 1 to 3 the liquid-containers 1 and 2, placed for instance on a heating body H, and the porous-body 3 75 are connected with one another by rods 4 and 5 traversing lugs 6 at the ends of the liquid-containers 1 and 2 and lugs 7 at the ends of the porous-body 3 so that the two liquid-containers can be adjusted, the one with regard 80 to the other. The rods 4, 5 have threaded ends 4^a, 5^a on which nuts 4^b, 5^b are screwed. By means of these rods the distance at which the liquid-containers 1, 2 are spaced can be increased or decreased. 85

In the form of construction shown in Figs. 4 to 6 the liquid-containers 1 and 2 are hingedly connected with the porous body. The porous body is composed of two elements 3 and 3^a connected the one with the other by a pivot-bolt 8 and hingedly connected to the corresponding liquid-container 1 or 2 by a bolt 9 or 10 respectively. Extensions 3^b and 3^c respectively of the two elements 3 and 3^a of the porous body project into the liquid-containers 1 and 2. The adjusting of the two liquid-containers is effected by means of rods 11 and 12 having each a handle 11^a, 12^a respectively at the middle and right hand thread on the one half and left hand thread on the other 90 95 100

half, said threaded portions being screwed through internally threaded lugs 13, 14 respectively of the liquid-containers 1 and 2 so that, by rotating the rods 11 and 12 in the one or other direction, the liquid-containers 1, 2 are moved the one towards the other or the one away from the other.

The liquid-containers 1 and 2 as shown in Figs. 7 to 9 are hingedly connected with the porous body composed of two elements. The elements 3 and 3^a of the porous body, connected the one with the other by a pivot-bolt 8, form a roof, the side walls of which form steps 3^a, 3^e. The object of this arrangement will be hereinafter explained. The elements 3, 3^a of the porous body are connected with the liquid-containers 1 and 2 by rods 9 and 10. From the bead-shaped lower end of the elements 3, 3^a strips of fabric 3^b, 3^c hang down which dip into the liquid in the containers 1 and 2. Tubular sockets 15^a, 15^b extending from the corresponding end of the liquid-containers 1, 2 are connected the one with the other by a flexible tube 15. To one of the tubular sockets, for instance the socket 15^a, a tubular socket 16^a, extending to a vessel 16, is connected said vessel containing a float 16^b which carries a valve-pin 16^c, the valve-seat 16^d for said valve-pin being arranged in a tubular socket 16^e, upwardly extending from the lid 16^d of the vessel 16. The tubular socket 16^e is connected by a tube 16^f to a reservoir, not shown, from which, when valve 16^c is opened, liquid flows into the vessel 16 and thence into the containers 1, 2 until the liquid in the casing and the containers has risen to the level at which the float closes the valve interrupting thus the liquid-admission. The level of the liquid in the containers 1 and 2 is constantly maintained at the same height. The containers 1 and 2 are connected the one with the other by means of rods 11, 12, having handles 11^a, 12^a on the middle and right hand threads on the one half and left hand threads on the other half screwed into lugs 13, 14 being internally threaded accordingly and which extend from the containers 1 and 2. The lugs 13, 14 are rotatably arranged in the walls of the containers and adapted to be secured in position by means of thumb-nuts 13^b, 14^b screwed on the shaft 13^a, 14^a of the lugs 13 and 14.

As shown in Figs. 10 to 12 the liquid-containers 1 and 2 are hingedly connected to a wire-frame consisting of two equal or unequal halves 17 and 17^a connected the one with the other by means of a rod 8, rods 9, 9^a serving for hingedly connecting the containers with the wire-frame. The side-part of each of the two halves 17, 17^a of the wire-frame is connected with the other half by means of rods 9^b, 9^c arranged between the rods 8 and 9. This wire-frame serves to hold a porous-sheet 3 of woven or knitted fabric, blotting paper or the like, the two

ends of which hang into the containers 1 and 2. The two containers are connected the one with the other by a rod 11 having a handle 11^a at the middle, left hand threads on the one half and right hand threads on the other half. The rod is screwed through internally threaded lugs 13 upwardly projecting from the liquid-containers 1, 2 respectively. 70

According to Figs. 14 and 15 the two frame elements 17, 17^a, hingedly connected the one with the other and with the corresponding liquid-contained 1 or 2, form together with the porous body 3 of fabric, blotting paper or the like a saddle roof. The connection of the liquid containers 1, 2 consists of rods 18 and tubes 18^a, the rods being telescoped into the tubes and adapted to be secured in position by means of screws 18^b. 75

In the form of construction shown in Fig. 13 a frame 17 is used which permits of providing steps in each half of the porous body 3 or to let sag the halves of the porous body at certain points as shown. 80

The liquid-containers 1 and 2 are connected the one with the other by a rod 40 pulled against the end-walls of the containers by means of a hook-shaped screw-bolt 41. 85

The frame 17, 17^a in the form of construction shown in Figs. 16 to 17 is made of wire and designed to support a separate vessel 20 for an antiseptic, pharmaceutic or cosmetic liquid in which a porous body 21 is arranged, the ends of which rest on the porous body 3 to transmit to the same liquid from the vessel 20. A rod 22 downwardly extending from the bottom-plate of the vessel 20 is adjustably mounted in sleeves 23 and 24, which are hingedly connected to the wire-frame 17, 17^a and adapted to be adjusted in vertical direction and to be secured by means of a set-screw 25 in any adjusted position. 90

The containers 1 and 2 in the form of construction shown in Figs. 18 to 21 may be adjusted in vertical direction, the halves of the frame 17, 17^a and the porous body 3 being adapted to be inclined either in upward direction, as shown in Fig. 18, or in upward and downward direction, as shown in Fig. 19, at different angles. 105

They might both be situated in a horizontal plane (Fig. 20) or sag as shown in Fig. 21. 110

The porous body 3, which may be of clay or the like (Figs. 1 to 9) or of fabric (Figs. 10 to 23), can have perforations 26, as shown in the top-plan-view 22, or perforations 26 and slots 26^a, as shown in Fig. 23. 120

The device illustrated in Fig. 18 is arranged above the plate P of a heating body H. The liquid-container 1 rests on a support 39 and has a guide-plate 38 designed to conduct the air to underneath the device for moistening and purifying the air. 125

One of the screw-bolts 48, having a hook- 130

shaped outer end 41 and designed for clamping the rods 40 on the end-walls of the liquid-containers 1 and 2, is shown in Fig. 24 of the drawing. The screw-bolts 41^a are inserted through holes in the end-walls of the containers 1 and 2 and secured by means of nuts 41^b. When the nuts 41^b are tightened, the rods 40 are pulled by the hooks 41 against the outer surface of the end-walls of the containers.

A modified device for connecting the liquid containers 1 and 2, shown in Figs. 25 to 27, consists of two lugs 27, 27^a and 28, 28^a respectively suitably spaced the one from the other and fixed on the end-walls of the containers 1 and 2, a nut 29, 30 respectively being clamped between the two corresponding lugs 27 or 28 so that it can neither shift nor rotate, one of said nuts 29, and 30 having right hand threads and the other left hand threads. A rod 42, having a handle 42^a at the middle, is inserted through the lugs 28, 28^a and nut 30 and through the lugs 27, 27^a and nut 29, the portions of said rod threaded through the nuts having correspondingly directed threads.

The adjusting device shown in Fig. 28 consists of a bar 43 adapted to be secured in lugs 14 of the liquid-containers 1, 2 by means of set-screws 14^c.

The liquid-containers 1 and 2 may be made of any convenient material, as clay, porcelain, metal or enamelled sheet-metal. The vessel 20 or several such vessels, containing the anti-septic, pharmaceutic or cosmetic preparation, may be arranged at any other point of the apparatus than shown, for instance between the liquid containers 1, 2 and the porous body 3.

40 By the step 3^d, 3^e in the porous body (Figs. 7 to 9 and 13) a so called return-head is produced for the liquid elevated by the porous body from the containers 1 and 2. On the first step 3^d or 3^e a certain quantity of liquid accumulates owing to the return-head formed by this step this liquid-quantity rising in the porous body up to the next higher step on which it accumulates again to rise up to the highest point of the porous body.

50 By this apparatus, the construction of which might be still further modified, is obtained that the air-currents in proximity of heating bodies are intercepted and conducted in such a manner that the air must flow along wet and rough surfaces and eventually traverse the same, in order to obtain a hygienic and aesthetic improvement of the air.

The apparatus serves:

- 1.—To moisten dry air up to a certain degree,
- 2.—To effect purification of the air in acting as a strip or passage-filter,
- 3.—To absorb gases of the dust-cokefying on the heating body,
- 4.—To produce and admix with the air

vapors having a hygienic and aesthetic effect,

5.—To regulate the effects mentioned under Numbers 1 to 4.

6.—To adapt itself to the numerous different arrangements of heating bodies.

I claim:—

1. An air-moistener and purifier comprising in combination liquid-containers, a porous body dipping into the liquid of said containers and extending above and between 75 said containers, and means for adjusting said liquid-containers with regard to each other and to said porous body.

2. An air-moistener and purifier comprising in combination liquid-containers, a porous body dipping into the liquid of said containers, and means for adjusting said liquid-containers with regard to each other and to 80 said porous body, said means consisting of lugs on the ends of said liquid-containers, 85 and of connecting rods in said lugs on which said liquid-containers can be adjusted.

3. An air-moistener and purifier as specified in claim 1, comprising a porous body which is step-shaped so that the height of the 90 step is shorter than the capillary elevating height of said porous body.

4. An air moistener and purifier, including independent liquid containers, a porous body terminally dipping into the respective 95 containers, and extended above the containers in step-shaped outline, and means for permitting adjustment of the containers relative to each other and to the porous body.

5. An air moistener and purifier, including 100 a plurality of independent containers, a porous body extending between and above said containers, the terminals of the body dipping into the liquid of said containers, and rods connecting the containers for adjustment 105 relative to each other.

In testimony whereof I affix my signature.
OTTO KARL LEOPOLD DRUBBA.
